UNITED STATES PATENT OFFICE.

ARTHUR LOCKE, OF TACOMA, WASHINGTON.

DRAIN-PIPE CLEANER.

Application filed September 20, 1924. Serial No. 738,787.

This invention relates to improvements in drain pipe cleaning devices, and more particularly to devices of that character especially adapted for the cleaning out of 5 clogged drain pipes from sinks, basins, tubs, toilets, etc., and which embody means whereby water under pressure may be used as a means for forcing a passage through the pipe to which the device is applied.

10 The principal object of this invention is to provide a device of the above character embodying a flexible cup that is applicable over the inlet of the pipe to be cleaned and to which the connection is made for receiving water under pressure and wherein the 15 construction of the cup is such that a further application of pressure within the pipe may be effected by compression of the cup.

It is also an object of the invention to 20 provide a device of the above stated character equipped with an interiorly located anchor hook for securing the cup tightly in place and to prevent leakage during the application of water pressure.

25 Other objects of the invention reside in the various details of construction of the cup, the disposition of the anchor hook and the means for tightening or releasing the latter.

30 In accomplishing these and other objects of the invention, I have provided the improved details of construction, the preferred forms of which are illustrated in the accompanying drawings, wherein—

35 Figure 1 is a side view of a drain pipe cleaning device embodying the present invention, shown partly in sectional view for the purpose of better illustration.

Figure 2 is a lower end view of the same.

40 Figure 3 is a view illustrating the use of the device for cleaning out the drain pipe of a bath tub or the like.

Figure 4 is a similar view illustrating the application and use of the device for cleaning 45 a closet.

Referring more in detail to the several views of the drawings—

1 designates, in its entirety, a device embodied by the present invention, comprising 50 a handle portion 2 of a desirable or convenient length having a downwardly opening cup 3 mounted at the lower end thereof; the handle having a ring 4 fixed thereto against which the cup seats.

55 In its preferred form of construction, the upper portion of the cup is made of hard

rubber, or other suitable material, and it is provided centrally on the outside with a socket 5 within which the end of the handle is seated and on the inside with a conically 60 tapered head 6 in which is formed a spherically curved, downwardly facing socket 7. Extending through this upper portion of the cup at one side of the socket 5 is a nipple 8 to which a flexible tube or hose 9 is 65 attached which at its outer end may be fitted over a faucet, or the like, 10, of a water pressure system.

The side wall portion 11 of the cup is formed integral with the upper portion but 70 is of thin, flexible rubber and is formed in a series of annular, corrugations as indicated at 12 which permits the cup wall to be compressed and to expand in its axial direction. It is of smaller diameter about its lower 75 edge or rim than across the upper portion and this provides that the lower end may be wedged within an outlet as will presently be described.

For the purpose of securing the cup in 80 place while water pressure is being applied to clean out a drain, I have provided an attaching or anchor hook 15 within the upper part of the cup having a shank 16 threaded into a sleeve 17 that is fixed with 85 in the lower end of the handle as shown in Figure 1.

Assuming that the device is so constructed, it is used in the following manner:

For cleaning the drain pipe of a sink, 90 basin, tub, or the like, the anchor hook is first extended sufficiently that the hook portion may be hooked over the usual spider or valve guide 20 in the inlet to the pipe; such spiders being provided either as a 95 mounting for a valve stem or to prevent the entrance of waste matter into the drain. The handle 2 is then rotated so as to draw the hook shank into the sleeve and to thereby tighten the cup edge against the base of the tub. The hose 9 is then attached to the faucet of a water pressure system, preferably a hot water connection, and the water admitted into the cup to force an outlet 100 through the clogged pipe. It is readily apparent that the pressure of water inside 105 the cup will act to expand the cup walls and thus more tightly clamp it against the base of the tub and leakage is impossible.

If it is desired to create an additional pressure, this can be effected by compression of the cup to drive the water therein into 110

the drain, and by a series of pumping movements of the cup operated by the handle, a drain can be quickly cleared.

For cleaning out a closet of the type shown in Figure 4, the lower end portion of the cup is fitted into the drain opening, then the water is turned on to force an outlet. Normally, the internal pressure created by the admittance of water into the cup will clamp the walls against the edges of the opening sufficiently that there will be no leakage, but should it be required, the cup can be compressed so that the conically tapered head 6 will wedge itself into the opening against the cup walls to clamp and hold them against the edges of the opening and thus prevent any possible leakage.

It is apparent that various changes in the details of construction of the device could be made without departing from the spirit of the invention, and for this reason I do not wish to be limited only to the construction herein illustrated.

Having thus described my invention, what I claim as new therein and desire to secure by Letters-Patent, is:

1. A device of the class described, comprising an inverted, cup-like member

formed of a yieldable, air and water-tight material, the side walls of the cup being formed in a series of annular corrugations and the upper portion of the cup having a socket in its outer face and formed inside the cup with a depending, conically tapered head and a handle fitted into the socket.

2. A device of the class described, comprising an inverted, cup-like member adapted to be applied over the inlet of a pipe to be cleaned, said cup having a relatively rigid upper portion and having relatively thin, flexible side walls that are annularly corrugated and adapted to be compressed in the axial direction of the cup, a handle rigidly fixed in the upper portion of the cup, a hook located within the cup having its shank threaded into the handle, the hook being adapted for application to a fixed member in the inlet of the pipe to be cleaned as a means of securing the cup in place, a nipple fixed in the upper portion of the cup and a hose connection on the nipple through which water under pressure may be admitted into the cup.

Signed at Tacoma, Washington, this 12th day of September, 1924.

ARTHUR LOCKE.
